STEAM-BOILER FURNACE.

1,217,492.

Specification of Letters Patent. Patented Feb. 27, 1917.

Application filed July 20, 1915. Serial No. 40,931.

To all whom it may concern:

Be it known that I, ORLAND D. ORVIS, a citizen of the United States, residing in the city of New York, borough of Manhattan, 5 county and State of New York, have invented a certain new and useful Steam-Boiler Furnace, of which the following is a specification.

This invention is a furnace for steam 10 boilers, the same being adapted, more particularly, for use in connection with water tube boilers of the Babcock and Wilcox type, wherein said water tubes are positioned in inclined relation across the furnace and the 15 gases and smoke are directed in a tortuous path between and around the tubes.

Experience shows that there is a cessation 20 in the combustion of the gases and smoke as they flow from the furnace to the stack, due to the reduction in the temperature of such 25 gases by contact with the water tubes, the heat being given off or transferred from the gases to the water present in the tubes, as a result of which the gases are burned more 30 or less imperfectly and they flow out of the stack more or less laden with carbon, thus giving rise to the so-called "smoke nuisance", particularly if soft coal is fed into the furnace.

Furthermore, in case the boiler is fired by 35 the use of a forced draft, the flow of gases is accelerated and fine particles or cinders are carried out of the stack by the outflowing gases, thus resulting in an objectionable cinder deposit upon the surrounding territory.

The object of my invention is to more 40 perfectly burn the smoke and gases within the furnace chamber, and to attain such improved combustion without decreasing the draft through the boiler. The means employed to secure these results are easy to install in new boilers or old boilers, are economical of manufacture, and are durable 45 and efficient in use.

In a practical embodiment of the invention I employ a baffle tile composed of refractory material, said baffle tile being substantially T-shaped, the head of the tile being 50 provided on the under surface thereof with curved surfaces inclined to the vertical medial line of the tile, whereas the shank of the tile is centrally positioned with re-

spect to the head and furthermore is, preferably, circular in cross section. The T-shaped tile is so proportioned that the head may easily be thrust or inserted between adjacent parallel tubes, after which the tile is given a quarter turn to position the head cross-wise of the adjacent tubes, and thereafter 55 the T-shaped tile is dropped into place in such manner that the curved and inclined under surface of the head rests upon the two adjacent tubes so as to be supported thereby. The tile thus spans the space between adjacent tubes, whereas the shank depends from the head of said tile, said shank being between and extending below adjacent tubes, whereby a number of these tiles are positioned 60 in the furnace chamber so as to become heated to a condition of incandescence, as a result of which the tiles act as 65 mechanical baffles in breaking up the smoke and gases and, further, said highly heated tiles act upon the gases flowing into contact therewith so as to burn the gases within the 70 furnace chamber.

The refractory tiles are positioned upon the lower course or tier of water tubes so as to depend below said tubes and extend into 80 the furnace chamber. Obviously, said tiles may be arranged or positioned in any desired order, but in order to employ a relatively large number of tiles so as to secure substantially uniform flow of gases and at 85 the same time so position said tiles that they will not appreciably check or retard the outflow of the gases to such an extent as to interfere with or reduce the draft, I preferably 90 arrange the tiles in groups and position the groups in staggered order with respect to each other, said groups of assembled tiles constituting what may be referred to as checkerwork tiles supported on the lower tier of water tubes and characterized 95 by free spaces, the aggregate area of which exceeds the cross sectional area of the stack or uptake whereby the gases are, in a measure, checked at the furnace chamber instead of being checked at the stack by 100 the damper in the usual manner, although it is apparent that the gases may be checked by the stack damper as usual.

Other features and advantages of the invention will appear in the course of the following detailed description.

In the drawings,

Figure 1 is a sectional elevation of a water tube boiler with my baffle tiles applied to the lower tier of water tubes.

5 Fig. 2 is a sectional plan view on the line 2-2 of Fig. 1.

Fig. 3 is a vertical cross section on the line 3-3 of Fig. 2.

10 Fig. 4 is a detail perspective view of one of the baffle tiles, on an enlarged scale.

Fig. 5 is a view illustrating the tile with the curved and inclined under surface whereby it is adapted to rest upon the inclined water tubes.

15 The baffle tile A is shown more particularly in Fig. 4 of the drawings, wherein said tile is substantially T-shaped and comprises a head *a* and a shank *b*, the entire tile being composed of refractory material, such as 20 fire clay. The head *a* is rectangular in plan view, whereas the shank *b* is substantially circular in cross section, but the horizontal cross sectional dimensions of the tile in either the head portion or the shank portion

25 is less than the space intervening adjacent parallel tubes of the boiler whereby the T-shaped tile is adapted to be inserted by passing it upwardly between the tubes, after which the tile is given a quarter turn for the 30 purpose of positioning the head *a* crosswise of the tubes in order that said head of the tile may rest upon the tubes, whereby the tile is supported by the tubes and the shank of said tile passes downwardly between the 35 tubes so that the lower portion of said shank is below the under surface of said tubes. It is apparent the tile should be molded of fire clay and baked in the usual manner so as to produce a tile composed of refractory material all the parts of which are integral.

40 The top, side and end faces of the head *a* are flat, but the under surface of the head is curved in one direction as at *c*, and is inclined at *d*, such inclination *d* of the under surface being illustrated more particularly in Fig. 5. It is apparent that the under surface of the head is curved as at *c* on both sides of the tile. The curved surfaces *c* enable the tile to rest firmly upon two adjacent tubes as 45 shown in Fig. 3, whereas the inclined surface *d* allows the tile to adjust itself to the inclination of the boiler tube, while at the same time the shank *b* hangs in a vertical position between and below the tubes. This 50 construction enables the depending fire clay tile to assume a position with respect to the tubes wherein the material of the shank portion of said tile is not likely to be injured or broken when in use within the furnace 55 chamber, and thus the durability of the tile is promoted by reason of the construction thereof and the position which the tile takes 60 when in use within the furnace chamber.

65 The tiles are adapted to be inserted individually into engagement with the lower-

most tier of inclined water tubes 10 of a new boiler or an old boiler, said boiler being shown in Figs. 1, 2 and 3 of the drawings, wherein 11 indicates the grate, 12 the bridge wall, 13 the front wall, 14 the front header, 70 15 one of the series of baffles through which the tubes are adapted to pass, and 16 the steam dome. The parts composing the boiler are usual in the art so that no particular description thereof is necessary, but in 75 Figs. 1, 2 and 3 the baffle tiles A of my invention are shown as being supported by the lowermost series of tubes 10, the latter being inclined over the furnace chamber 17.

The baffle tiles A may be positioned in any 80 desired order upon the lowermost series of inclined water tubes, so that said tiles are directly over the furnace chamber in a manner to expose the tiles, and particularly the depending shanks thereof, to the gases and 85 smoke flowing into contact therewith, whereby the tiles composed of refractory material will be heated by the combustible gases to a condition of incandescence. The tiles act to mechanically break up the current of smoke 90 and gases, and when heated to a condition of incandescence said tiles burn the gases and the smoke, thereby securing more perfect combustion of said gases, as a result of which the carbon in the smoke is substantially eliminated and the gases issue from 95 the stack in the form of a relatively thin and almost invisible vapor.

The tiles are inserted individually through the spaces intervening the tubes of 100 the lower series, for which purpose the horizontal cross sectional dimensions of the tile in one direction is less than the space intervening the adjacent tubes. When the tile is to be placed in position, it is held in the 105 hand in such manner that the head and shank can be passed in an upward direction between two adjacent tubes, and after the head shall have been raised above the tubes then the tile is turned or partially rotated 110 (through an arc of 90°) so as to position the head *a* crosswise of the tubes, the diameter of the shank *b* permitting the tile to be turned freely between the tubes, and, finally, the tile is lowered so that the curved under 115 surfaces *c* will be in contact with the top and side surfaces of two adjacent tubes, all as clearly illustrated in Fig. 3. By thus manipulating the tile it can be introduced into new or old boilers as desired, the tile 120 can be placed in position by unskilled labor and within a few minutes time, said tile rests upon the lowermost tubes of the boiler and the tiles occupy positions wherein the material is not likely to burn off by the intense 125 heat of the gases thereby securing economy and durability.

A preferred method of assemblage of the tiles is illustrated more particularly in Fig. 130

2 of the drawings wherein said tiles are assembled in groups and the tiles of one group are in staggered relation to the tiles of another group for the purpose of producing 5 openings at suitable intervals, which openings are unobstructed by the tiles with a view to permitting the free outflow through said openings of the remaining gases. The tiles are assembled in the following way: A 10 series of tiles are introduced successively between two of the tubes and one of the tiles is allowed to rest against the baffle 15, the other tiles of the group being in contact with each other. Another group of tiles is 15 positioned upon the third and fourth tubes so that one tile is in contact with the baffle and the other tiles of the same group are in contact with each other, but it is apparent that the space between the second and third 20 tubes is left open. Successive groups of tiles are then assembled so as to leave openings between the groups, thus completing the first row. A second row of tiles is now assembled so that the tiles of the second 25 row are staggered with respect to the tiles of the first row, the tiles of the groups being positioned so as to leave openings between said groups, which openings formed by the groups of tiles comprising the second row are in alternate or staggered relation to the groups of tiles in the first row. A third, and other successive rows, composed of 30 groups of tiles are assembled until practically all the tubes are partially covered by groups of tiles, but these tiles are assembled so that the aggregate area of the openings will exceed the cross sectional area of the 35 stack or uptake, thus providing ample space for the outflow of the gases without substantially checking the draft created through the furnace chamber by the stack or uptake. The baffles assembled as shown in Fig. 2 will retard the flow of gases by reason of the contact of such gases with the 40 baffles, but more particularly the shanks thereof, and as said baffles are heated to a glowing or incandescent condition the flow of gases into contact therewith will set up a 45 combustion of the gases so as to substantially increase the heat units.

50 My invention may be used in connection with any style of water tube boiler having either a natural draft or a forced draft, but when forced draft is used to blow air or 55 steam and air through the grate chamber the baffles will not only check the outflow of the gases so as to set up a proper combustion thereof, but said baffles will deflect the fine particles of combustible matter or cinders, thus precluding the deposit of cinders or soot upon the territory adjacent to the 60 stack or uptake.

65 It is apparent that any desired number of tiles may be assembled in each group, although in Fig. 2 each group is shown as

consisting of three tiles; thus, the groups may consist each of two, four or more tiles. Furthermore, the tiles may be singly positioned upon the tubes, preferably in staggered order.

70 An important feature of my invention is the assemblage of tiles into contact so as to retain them in position by engagement of one tile with another or with others, whereby displacement of the tiles upon the inclined tubes is precluded by the engagement of said tiles with one another. Owing to the inclination of the tubes, the tiles have a tendency to slide thereon toward the lowest part of said tubes. Accordingly, the tiles 75 in the lower row rest against the baffle 15; the tiles in the second row are in contact with the tiles of the first row so as to prevent the second row of tiles from sliding out of place, and so on throughout the remaining rows, all the tiles being in engagement 80 so as to retain them in their proper operative positions. Furthermore, the head of each tile is so proportioned that its end portions extend beyond the centers of the 85 adjacent tubes upon which the tile is supported, and thus the end portions or corners of one tile are adapted for overlapping engagement with similar parts of two, three 90 or more tiles adjacent thereto.

95 Having thus fully described the invention, what I claim as new, and desire to secure by Letters Patent is:

1. A substantially T-shaped baffle tile for water tube boilers comprising a head and a shank composed of refractory material, the under surface of said head being curved to fit said tubes and said curved under surface being inclined to the vertical axis of the tile whereby the shank is positioned vertically between the tubes when the head rests upon said tubes, said tiles being supported by the heads thereof resting upon the boiler tubes and the shanks of said tiles depending below said boiler tubes.

100 2. A substantially T-shaped baffle tile for water tube boilers comprising a head and a shank composed of refractory material, the transverse dimensions of the head and shank in one direction being less than the space 105 intervening adjacent water tubes so that the tile is adapted to be inserted for the head to pass between said adjacent tubes and thereafter the tile may be turned for the head to rest upon said tubes, said tiles being supported by the heads thereof resting upon the boiler tubes and the shanks of said tiles depending below said boiler tubes.

110 3. The combination with the water tubes of a boiler, of substantially T-shaped baffle 115 tiles each comprising a head and a shank composed of refractory material, the cross sectional dimensions of said tile in one direction being less than the space intervening 120 adjacent water tubes, said baffle tiles being 125

insertible individually in an upward direction between the lowermost tubes and thereafter each tile is turned to a position for its head to lie crosswise of said lower tubes and 5 to rest thereon, said tiles being supported by the heads thereof resting upon the boiler tubes and the shanks of said tiles depending below said boiler tubes.

4. The combination with inclined water 10 tubes of a boiler, of substantially T-shaped baffle tiles each comprising a head and a shank composed of refractory material, the under surface of said head being curved and being inclined and said tiles being individually insertible in an upward direction through the space intervening adjacent tubes, each tile subsequent to the initial upward movement being turned for the head 15 to span the space intervening the adjacent tubes so that the curved and inclined under surface of the head will contact with adjacent tubes and the shank of said tile is adapted to hang vertically between said tubes.
5. A baffle tile for water tube boilers, substantially T-shaped and comprising a head and a shank composed of a single piece of refractory material, the cross sectional dimensions of the tile in one direction being 20 less than the width of the space intervening adjacent parallel tubes whereby the tile is adapted to be inserted by passing it upwardly between the tubes and thereafter the tile is turned for the head thereof to lie 25 crosswise and to rest thereon, the shanks of said T-shaped tiles depending below the boiler tubes.
6. A baffle for water tube boilers comprising

ing substantially T-shaped tiles assembled in groups, said groups of tiles being staggered with respect to each other and with 40 the end tiles of each group in contact with similar tiles of adjacent groups, each tile comprising a head and a shank composed of refractory material and said tile being positioned with the head thereof in contact with 45 adjacent parallel tubes and with the shanks of said tiles depending below said boiler tubes.

7. A baffle for water tube boilers comprising substantially T-shaped tiles assembled 50 in groups and with the groups positioned to leave unobstructed openings at intervals between said tubes, certain tiles of each group being in contact with certain tiles of the other groups and each tile comprising a 55 head and a shank whereof the head is supported by adjacent tubes and the shank depends between said tubes so as to be heated to incandescence by the gases flowing into contact therewith.

8. A baffle for water tube boilers comprising substantially T-shaped tiles assembled 60 in groups and supported by the lower tubes of said boiler, each group being staggered with respect to other groups so as to leave 65 openings at intervals and the tiles of each group being inserted individually between the adjacent tubes, said T-shaped tiles having shanks depending between the boiler tubes.

In testimony whereof I have signed my name to this specification.

ORLAND D. ORVIS.
